UNITED STATES PATENT OFFICE.

JAMES BUCKLER, OF PHILADELPHIA, PENNSYLVANIA, ASSIGNOR TO CROMPTON & KNOWLES LOOM WORKS, A CORPORATION OF MASSACHUSETTS.

METHOD OF WEAVING PILE FABRICS.

959,306.

Specification of Letters Patent. Patented May 24, 1910.

Application filed October 23, 1909. Serial No. 524,145.

To all whom it may concern:

Be it known that I, JAMES BUCKLER, a citizen of the United States, residing at Philadelphia, in the county of Philadelphia and State of Pennsylvania, have invented 5 certain new and useful Improvements in Methods of Weaving Pile Fabrics, of which the following is a specification.

My invention relates to weaving pile 10 fabrics, and particularly to an improved method of weaving pile fabrics of the class in which the pile tuft yarn is separate from the binder and stuffer warps, and the weft threads, and is inserted in a series of rows 15 between the binder and stuffer warps, to form a cut pile surface or face on the fabric, as moquette carpets, and Axminster carpets.

The object of my invention is to improve 20 upon the ordinary method of weaving pile fabrics of the class above referred to.

In the ordinary method of weaving pile 25 fabrics of the class above referred to, a series of pile tufts are inserted between the warps, and a weft thread is inserted into the shed, and then the free ends of the pile tufts are moved upwardly between the warps, from the underside of the weft thread, by a 30 comb, and pass up on the opposite side of the weft thread, and partially encircle the weft thread, which acts to hold the tufts in the fabric, after the weft threads are beaten up.

In my improved method of weaving pile 35 fabrics of the class referred to, instead of passing the pile tufts around the weft or filling threads, they are passed around a stuffer warp, or one of the binder warps, that is around the threads which extend in the direction of the length of the fabric.

In carrying out my improved method 40 of weaving pile fabrics of the class referred to, I preferably use a reed having the dents thereof so formed or shaped, that in weaving the fabric, certain stuffer or warp threads are moved to one side at the proper time, to 45 allow the tube frame to carry the ends of the pile tufts down between the warps, and the ends of the pile tufts are then moved up between the warp threads, by the operation of the comb, to cause the pile tufts to be carried around and partially encircle a stuffer, or one of the binder warp threads.

Each series of pile tufts extend in the di-

rection of the length of the fabric, and partially encircle, preferably, a single stuffer, or binder warp thread.

55

I have shown in the drawings, on an exaggerated scale, diagrammatic views to illustrate my improved method of weaving pile fabrics of the class referred to, and mechanism which may be used for carrying out my 60 improved method, sufficient to enable those skilled in the art to understand the construction and operation of my improvements.

Referring to the drawings:—Figure 1 is a diagrammatic view showing the shed 65 formed by the first position of the harnesses, and the free end of a pile tuft inserted. Fig. 2 shows the shed formed by the second position of the harnesses, and a pile tuft passed upwardly around a stuffer warp. 70 Fig. 3 shows the shed formed by the third position of the harnesses, and a pile tuft cut off. Fig. 4 shows the shed formed by the fourth position of the harnesses. Fig. 5 is a section, on line 5, 5, Fig. 1, looking in 75 the direction of arrow a, same figure. Fig. 6 corresponds to Fig. 1, but shows a modified construction of the reed dents, to cause a pile tuft to pass around a binder warp, instead of a stuffer warp. Fig. 7 corresponds to Fig. 2, but shows a pile tuft 80 passed around a binder warp in the upper plane of the shed. Fig. 8 corresponds to Fig. 3, but shows a pile tuft passed around a binder warp in the upper plane of the 85 shed. Fig. 9 corresponds to Fig. 4, but shows a pile tuft passed around a binder warp in the upper plane of the shed, and, Fig. 10 is a section, on line 10, 10, Fig. 6, looking in the direction of arrow b, same 90 figure.

In the accompanying drawings, 1 is the lay beam, having the dents 2 of the reed mounted thereon.

3 is a bar, which carries the comb 4 in the 95 usual way.

5 are the tuft yarn carriers or tubes, which guide a pile tuft yarn 6 from the spool, not shown.

7 is a stuffer warp, and 8 and 9 are binder 100 warps, and 10 is a double filling or weft thread.

I will first describe my improved method of weaving pile fabrics in which the pile

tufts are passed around the stuffer warps, as shown in Figs. 1 to 5, inclusive.

The dents 2 of the reed are formed with a double offset 2', on one side, which causes the stuffer warp 7 to be moved sidewise, as shown at the left in Fig. 5. The stuffer warps are moved to the left by the offset 2' in the dents 2 of the reed, and leave a space between a stuffer warp 7 and the binder warps 8, and 9, see Fig. 5, which is sufficient for the free end of the pile tuft yarn 6 to be inserted between the stuffer 7, and binder warps 8 and 9, as shown in Fig. 1, in which figure the lay 1, and reed 5 comprising the dents 2, have been moved halfway toward the fell of the fabric, and remain in this position to allow the tube 5 to put the end of the pile tuft yarn 6 down between a stuffer warp 7, and the binder 20 warps 8 and 9.

By the movement of the harnesses, the position of the stuffer warp 7, and binder warps 8 and 9 are changed to the position shown in Fig. 2, and the operation of the comb 4 moves the free end of the pile tuft yarn 6 from below the stuffer warp 7, and around the stuffer warp 7, and up between the stuffer warp 7, and the binder warps 8 and 9. The continued operation of the loom 25 will sever the tuft yarn 6, as shown in Fig. 3, and withdraw the tuft yarn carrier 5, leaving the pile tuft 6 around the stuffer warp 7, the shed having been changed by the movement of the harnesses, as shown in Fig. 3, to carry the binder warp 8 into the lower plane of the shed for the insertion of a double filling 10. The filling 10 is then beaten up by the reed to the fell of the fabric, as shown. The next movement of the 30 harnesses changes the shed, as shown in Fig. 4, when the stuffer warp 7 is brought to the lower plane of the shed, and another double filling 10 is inserted in the upper plane of the shed and beaten up. These operations 35 are repeated throughout the length of the fabric.

I will now describe my improved method of weaving pile fabrics in which the pile tuft is passed around a binder warp instead of a stuffer warp, see Figs. 6 to 10. The dents 2 of the reed have in this instance a single offset at 2'', which causes the warps in their downward movement, to be moved sidewise of the warps which remain in the 50 upper plane of the shed, as shown at the left in Fig. 10, leaving a space between the binder warp 8 in the upper plane of the shed, and a stuffer warp 7 and a binder warp 9 in the lower plane of the shed, sufficient for the end of the pile tuft yarn 6 to be inserted, as shown in Figs. 6 and 10. The position of the warps are then changed to the position shown in Fig. 7, and the operation of the comb 4 passes the free end of

the pile tuft yarn 6 around the binder warp 65 8 in the upper plane of the shed of the fabric. The continued operation of the loom will sever the pile tuft yarn 6, and withdraw the tuft yarn carrier 5, the movement of the harnesses having changed the 70 shed, as shown in Fig. 8, to carry the binder warp 8 into the lower plane of the shed for a double filling 10 to be inserted. The filling 10 is then beaten up by the reed to the fell of the fabric for the next movement of 75 the harnesses to change the shed, as shown in Fig. 9. The stuffer warp 7 is also brought to the lower plane of the shed, and another double filling 10 is inserted in the upper plane of the shed, and beaten up by 80 the lay. The binder warp 9 is now in the upper plane of the shed, preparatory to the next insertion of the pile tuft yarn 6, to be passed around said binder warp 9, and these operations are repeated throughout the 85 length of the fabric, causing the pile tuft yarn to be passed around the binder warp in the upper plane of the fabric.

In my improved method of weaving pile fabrics the pile tufts are passed around 90 either the stuffer warps, which extend through the body of the fabric, or around the binder warps which extend in the upper plane of the fabric, and are thus securely attached to the body of the fabric. 95

It will be understood that any suitable mechanism for carrying out my improved method of weaving pile fabrics may be used.

Having thus described my invention, what I claim as new and desire to secure by Letters Patent is:—

1. An improved method of weaving pile fabrics which have the pile tufts separate from the body of the fabric, and passed around the stuffer warps, and which consists in moving the stuffer warps to one side, to leave a space between the stuffer warps and the binder warps, inserting the free ends of the pile tuft yarns between the stuffer warps and the binder warps, changing the shed, moving the free ends of the pile tuft yarns around the stuffer warps, and up between the stuffer warps and the binder warps, cutting the pile tuft yarns, changing the shed, inserting a filling in the 110 lower plane of the shed, and beating up said filling, changing the shed again, and inserting a filling in the upper plane of the shed, and beating up said filling.

2. An improved method of weaving pile 120 fabrics which have the pile tufts separate from the body of the fabric, and passed around a binder warp, and which consists in moving some of the binder warps to one side, to leave a space between the binder 125 warps in the upper plane of the shed, and the stuffer warps and the binder warps in the lower plane of the shed, inserting the

free ends of the pile tuft yarns between the binder warps in the upper plane of the shed, and the stuffer warps and the binder warps in the lower plane of the shed, changing the 5 shed, moving the free ends of the pile tuft yarns around the binder warps in the upper plane of the shed, cutting the pile tuft yarns, changing the shed, inserting a filling

in the lower plane of the shed, and beating up said filling, changing the shed again, 10 and inserting a filling in the upper plane of the shed, and beating up said filling.

JAMES BUCKLER.
